[57] **CLAIM**

The ornamental design for a microwave cooking utensil, as shown and described.

DESCRIPTION

FIG. 1 is a top, front perspective view of a microwave cooking utensil showing our new design;

FIG. 2 is a top front perspective view thereof in an open condition;

FIG. 3 is a top plan view thereof;

FIG. 4 is a front elevational view thereof;

FIG. 5 is a bottom plan view thereof;

FIG. 6 is a rear elevational view thereof; and

FIG. 7 is a right side elevational view thereof, the left side being a mirror image thereof.

FIG. 1

FIG. 3

FIG. 4

FIG. 5

FIG. 6

FIG. 7
